UNITED STATES PATENT OFFICE.

ARTHUR D. SABORSKY, OF LAKewood, OHIO.

BATTERY-LIGHT ATTACHMENT.

1,363,924.

Specification of Letters Patent. Patented Dec. 28, 1920.

Application filed December 30, 1914, Serial No. 879,675. Renewed March 25, 1920. Serial No. 368,695.

To all whom it may concern:

Be it known that I, ARTHUR D. SABORSKY, a citizen of the United States, residing at Lakewood, in the county of Cuyahoga and 5 State of Ohio, have invented certain new and useful Improvements in and relating to Battery-Light Attachments, of which the following is a specification.

This invention relates to improvements in 10 battery lamp attachments, more particularly to a device for holding a miniature electric bulb upon any well known type of dry cell which has a pair of outwardly extending electrodes at one end thereof.

15 An object of my invention is to provide a simple, inexpensive, effective and durable attachment which may be quickly and easily attached to and detached from the dry cell, and may be employed either for flash 20 lighting or continuous lighting purposes as desired.

Other objects of my invention will be obvious from the description of devices embodying it which I have herein selected for 25 the purpose of illustration.

Figure 1 shows an attachment embodying my invention partly in side elevation and partly in section.

Fig. 2 is a top plan view of the same. 30 Fig. 3 illustrates in full lines the attachment connected to one standard form and in dotted lines to another standard form of dry cell.

Fig. 4 is a perspective view of a dry cell 35 with one of my attachments fitted thereto.

Figs. 5 and 6 show modifications.

In the drawings, 1 is a combined reflector support and electrical conductor. It preferably consists of a strip of resilient sheet 40 metal having a section 1^a perforated at 1^b, a curved offset section 1^c extending from the section 1^a and bent back upon itself as indicated at 1^d to form a resilient base each portion of which is longitudinally perforated as indicated at 1^e.

2 is a reflector of suitable shape preferably provided with a cylindrical, tubular base 2^a which is projected through the opening 1^b of the combined reflector support and 50 conductor 1, and has its free end upset against the under side of the element 1 so as to hold the reflector in proper position thereon.

3 is an electric bulb, of standard construction, having a suitable filament with

one end electrically connected to the shell 3^a of the plug 3' and its other end electrically connected to the central electrode 3^b. The plug 3' is inserted through the tubular base of the reflector and is held in proper 60 position by a suitable nipple 4.

5 is a dry cell of standard construction having the electrodes 6 and 7. The cell is preferably of curvilinear shape in cross section.

65 In order to fit one of my attachments to the dry cell all that is necessary is to see that the thumb screw 6' for the electrode 6 is removed, whereupon this electrode is projected through the slots 1^e of the combined reflector support and conductor 1. The thumb nut 6' is then screwed back upon the electrode so as to engage the base section 1^d of the element 1. If it is desired to use the device for the purpose of flashing light, 70 the thumb nut 6' is set up so that the central electrode 3^b at the lower end of the plug 3' is adjacent to but does not engage with the electrode 7 of the dry cell, as shown in Fig. 3. The operator then presses downwardly 75 upon either the reflector or its support in order to engage the bulb electrode 3^b with the lamp electrode 7, whereupon an electrical circuit is established between the electrodes 6 and 7 through the instrumentality 80 of the element 1, bulb electrode 3^a, the filament within the bulb and the bulb electrode 3^b.

85 The instant that pressure on the device is relieved by the operator, the bulb will 90 spring away from the electrode 7 under the influence of the spring action of the metal of which the element 1 is made.

The elongated slots 1^e in the foot portion 95 1^d are provided to enable the device to be readily adjusted to dry cells in which the distance between the electrodes 6 and 7 may vary, but more particularly in connection with the curved offset portion 1^c, to accommodate for different heights between the top 100 1^d of the electrode 7 and the top of the dry cell with which the lower wall of the foot 1^d engages, as illustrated in Fig. 3, where two different constructions of standard dry cells are shown.

105 In Fig. 2 I have shown the upper surface of the foot or base section 1^e at either side of the slot therethrough, indented at 1^e so that the lower surface of the electrode thumb nut 6', when engaging with the 110

rough surface caused by these indentations will serve to hold the device properly in place upon the dry cell.

To those skilled in the art of making devices of the class described, many alterations in construction and widely differing embodiments and applications of my invention will suggest themselves, without departing from the spirit and scope thereof. My disclosures and the descriptions herein are purely illustrative and are not intended to be in any sense limiting.

For example, in Fig. 3, I have illustrated a modification in which the reflector is formed in the metal which constitutes the element 1. Where a relatively small reflector will suffice this device will be found to be somewhat cheaper than the one illustrated in Figs. 1 and 2.

20 It will be noted that if the proper relationship is established to hold the electrode 3^b in contact with the battery electrode 7, that the circuit may be disconnected or re-established simply by swinging the holder 25 about the axis of the electrode 6 so as to force the electrode 3^b out of and into engagement, respectively, with the electrode 7.

In Figs. 5 and 6 I have illustrated an attachment in which the contact between the 30 central electrode 3^b of the bulb and the battery electrode 7 is established merely by swinging the bulb about the axis of the electrode 6. In this modified construction instead of bending the metal back upon itself, 35 forming a resilient foot which engages with the top of the dry cell at the electrode 6, I have extended the metal outward beyond the electrode 6 and then downwardly as indicated at 1^f to form a handle. The handle 40 1^f may also serve as a rest for the cell, thus permitting the latter to be placed on its side on the floor or other suitable support to throw the light in various directions. In this construction furthermore I have bent 45 the reflector end of the support and conductor angularly so as to reflect the light more or less laterally relative to the dry cell.

It will be noted that in view of the fact 50 that electrical contact is made and broken directly between the central electrode of the bulb and the battery electrode with which it alines, that it is not necessary to provide any additional insulation either for the battery electrode or bulb electrode, in other 55 words my attachment does not require the use of any insulating material other than that between the electrodes of the bulb itself.

What I claim is:

1. In a device of the class described, a 60 continuous strip of resilient metal having formed through it intermediate of its ends two openings, one disposed to have extended through it one electrode of a dry cell to facilitate mechanical and electrical connection of said metal strip with said electrode,

and the other being disposed to aline with the other electrode of the dry cell, and a reflector carried by said strip and having a bulb opening disposed to register with the last described opening through said strip of 70 metal.

2. In a device of the class described, a continuous strip of resilient metal having formed through it intermediate of its ends two openings, one disposed to have extended 75 through it one electrode of a dry cell to facilitate mechanical and electrical connection of said metal strip with said electrode, and the other being disposed to aline with the other electrode of the dry cell, a reflector carried by said strip and having a bulb opening disposed to register with the last 80 described opening through said strip of metal, and a lamp bulb having its plug end extended through the bulb opening in said 85 reflector.

3. In a device of the class described, a continuous strip of resilient metal bent back upon itself at one end to form a resilient 90 base, both walls of which have openings therethrough alined to receive a battery electrode which extends therethrough, and a reflector carried by said strip and having a bulb opening disposed to register with the other battery electrode.

4. In a device of the class described, a section of resilient sheet metal, and a reflector supported at one end of said section of resilient metal and having a bulb opening disposed to aline with one electrode of 100 a battery, said section of sheet metal extending substantially at an angle to the axis of said bulb opening, then downwardly and outwardly and then back upon itself to form a resilient base, the walls of said resilient 105 base being longitudinally slotted to receive the other battery electrode for permitting the adjustment of said metal section bodily to and fro properly to position said bulb opening in alinement with said battery electrode with which it is adapted to aline.

5. In a device of the class described, a section of resilient sheet metal, and a reflector supported intermediate the ends of 115 said section of resilient metal and having a bulb opening disposed to aline with one electrode of a battery, said section of sheet metal extending substantially at an angle to the axis of said bulb opening, then downwardly and outwardly and then back upon itself to form a resilient base, the walls of said resilient base being longitudinally slotted to receive the other battery electrode and the upper surface of the upper wall of 120 said resilient base being indented adjacent to the perforation therethrough.

6. In a device of the class described, a continuous strip of resilient metal, and a reflector carried by said strip and having a bulb opening disposed to aline with one elec- 130

trode of a battery, said metal strip being longitudinally slotted intermediate its ends to receive the other electrode of said battery and to be electrically and mechanically connected therewith, whereby said metal strip may be moved bodily to and fro relatively to said electrode properly to position said bulb opening in alinement with said battery electrode with which it is adapted to aline.

10. 7. In a device of the class described, a battery having a pair of electrodes, a section of resilient metal electrically and swingably connected to one of said battery electrodes, and an electric bulb carried by said section of resilient metal and having one of its electrodes electrically connected to said section of resilient metal and its other electrode disposed to engage with the other electrode of the said battery and movable into and out of engagement therewith, either by swinging it about the longitudinal axis of the first mentioned battery electrode, or by springing it down and up.

8. In a device of the class described, a battery having a pair of electrodes, a section of metal electrically and swingably connected to one of said battery electrodes, and an electric bulb carried by said section of metal and having one of its electrodes electrically connected to said section of metal and its other electrode disposed to engage with and disengage the other electrode of said battery by swinging said section of metal and bulb about the longitudinal axis of the first mentioned battery electrode.

9. In a device of the class described, a continuous strip of resilient metal, a reflector carried by said strip and having a bulb

opening disposed to aline with one electrode of a battery, said metal strip being longitudinally slotted intermediate its ends to receive the other electrode of said battery and to be electrically and mechanically connected therewith, whereby said metal strip may be moved bodily to and fro relatively to said electrode properly to position said bulb opening in alinement with said battery electrode with which it is adapted to aline, and said strip having one end arranged to be disposed at one side of the battery cell of curvilinear cross-section, to support the said cell on its side and with the bulb opening in alinement with the electrode with which it is adapted to aline.

10. In a device of the class described, a battery having a pair of electrodes, one extending from one side and the other from the center of one end thereof, a continuous metal strip having an opening formed through it to receive said side electrode and to be electrically and swingably connected thereto, and an electric bulb carried by said metal strip and having one of its electrodes electrically connected thereto and its other electrode disposed to engage with and disengage the centrally disposed electrode of said battery when swung to and fro with said strip about the axis of said side battery electrode.

In testimony whereof I affix my signature in the presence of two witnesses.

ARTHUR D. SABORSKY.
